FIREPLACE SCREEN HANGER

Peter F. Pedersen, Allen Park, Mich.

Application February 7, 1947, Serial No. 727,081

2 Claims. (Cl. 248—145)

1

My invention relates to a new and useful improvement in a fireplace screen hanger.

It is an object of the present invention to provide a screen closure across the opening of a fireplace to prevent sparks or live coals from being thrown into the room, and to pivotally hang the screens on a post whereby they may be swung into closing position across the opening of the fireplace, or swung outwardly to lie adjacent the wall of the room.

It is another object of the present invention to provide a hanger for the screen which can be readily mounted in a fixed permanent relation within the fireplace without necessitating any drilling or securement by bolts, screws or the like of the hanger to the wall of the fireplace.

It is a further object of the present invention to provide a screen having a hanger which is adjustable to fit in various size fireplaces.

It is a still further object of the present invention to provide a fireplace screen hanger of the class described which is simple in structure, attractive in appearance, economical of manufacture and highly efficient in use.

Other objects will appear hereinafter.

It is recognized that various modifications and changes may be made in the detail of structure illustrated without departing from the invention itself and it is intended that such shall be embraced within the scope of the claims which form a part hereof.

Forming a part of this specification are drawings in which,

Fig. 1, is a fragmentary, elevational view of a wall illustrating a fireplace with the invention applied and having a part thereof broken away,

Fig. 2, is a sectional view taken on line 2—2 of Fig. 1,

Fig. 3, is a fragmentary, sectional view taken along line 3—3 of Fig. 1,

Fig. 4, is a fragmentary, sectional view taken along line 4—4 of Fig. 1.

Shown in the drawing is a pair of screens 10 and 11, each of which is similarly constructed and pivotally mounted so that a description of one will suffice for both. The screen 10 is held in a channel frame 12 which extends around its four sides and is held therein by a channel 14 which is pressed into the channel 12, the screen 10 being wedged between the channel 14 and the channel 12. Extending outwardly from the rear of the channel 12, on its top and bottom wall, are lugs 15 to which is pivotally secured by a suitable pin the end of the V-shaped bracket arm 16. The vertex of the V-shaped arm 16 is secured

2

by the connecting member 17 to a sleeve 18. Diagonal braces 19 extend between to join a respective end of bracket arm 16 with a respective end of sleeve 18. The sleeve 18 is positioned to rotate about the rod 21. One end of rod 21 is threaded for receiving a cap 22. The upper end of the cap 22 is provided with a socket for receiving the lower end of the sleeve 18. The opposite end of the rod 21 is threaded for receiving an adjustment nut 23, the lower end of which is provided with an extended sleeve section 24 to embrace the sleeve 18. The opposite end of the adjustment nut 23 is provided with a reduced section 26 to serve as a shoulder upon which is set the cap 27 having a central bore 28 extending therethrough for the projection of the upper end of the rod 21 therethrough as the nut 23 is threaded downwardly on the rod 21.

In mounting the hanger within the fireplace, 20 the cap 22 is rested upon the floor of a fireplace and the rod 21 with the sleeve 18 thereon extended in a vertical upright position so that the cap 27 will abut against the top 9 of the fireplace opening. By rotating the adjustment nut 23, 25 the cap 27 will be pressed against the ceiling to tightly wedge the rod 21 between the top 9 and the floor of the fireplace. It will be noted that by this arrangement, the hanger can be used for various size fireplaces without affecting or in any way interfering with the free rotation of the sleeve 18 about the rod 21. As the sleeve 18 is free to rotate on the rod 21, the screen can be easily swung either to an open or closed position. When swung to open position, the screen will be against the face of the wall 7.

35 What I claim is:

1. A fireplace screen mounting of the class described, comprising an elongated post; a sleeve rotatably embracing said post, said post projecting beyond opposite ends of said sleeve, the opposite ends of said post being threaded; an adjusting nut threaded on one end of said post and provided with a socket for embracing one end of said sleeve; a cap threaded on the lower end of said post and adapted for engaging a stationary body 40 45 the upper end of said cap having a socket for receiving the lower end of said sleeve; a cap embracing the opposite end of said post in slidably relation thereto, and adapted for engaging a stationary body spaced from said first named stationary body, the threading of said adjusting nut effecting a clamping of said caps against said stationary bodies for retaining said post in fixed relation to said stationary bodies.

2. A fireplace screen mounting of the class de-

scribed, comprising an elongated post; a sleeve rotatably embracing said post, said post projecting beyond opposite ends of said sleeve, the opposite ends of said post being threaded; an adjusting nut threaded on the upper end of said post and provided with a socket for embracing the upper end of said sleeve; a cap threaded on the lower end of said post and adapted for engaging a stationary body the upper end of said cap having a socket for receiving the lower end of said sleeve; a cap embracing the opposite end of said post in slidable relation thereto, and adapted for engaging a stationary body spaced from said first named stationary body, the threading of said adjusting nut effecting a 15 clamping of said caps against said stationary bodies for retaining said post in fixed relation to

said stationary bodies; and supporting members secured to and projecting outwardly from said sleeve, said sleeve being rotatable on said post.
